Patented Dec. 28, 1926.

UNITED STATES PATENT OFFICE.

JAMES M. MORGAN, OF BRISTOW, OKLAHOMA.

ROAD CULVERT.

Application filed August 6, 1925. Serial No. 48,606.

This invention relates to certain improvements in road culverts and has relation more particularly to a device of this general character constructed from reinforced cementitious material, and it is an object of the invention to provide a device of this kind comprising a plurality of separable sections which may be readily assembled and effectively maintained in such assembly.

It is also an object of the invention to provide a device of this kind constructed in a manner to provide a substantially flat top and wherein said top is constructed in a manner to permit the same to be effectively locked to side or vertical walls of the culvert.

The invention consists in the details of construction and in the combination and arrangement of the several parts of my improved road culvert whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:—

Figure 1 is a view in perspective illustrating a culvert constructed in accordance with an embodiment of my invention and in assembled relation;

Figure 2 is a longitudinal vertical sectional view taken through the structure as illustrated in Figure 1;

Figure 3 is a view in perspective of an end bottom section unapplied;

Figure 4 is a view in perspective of an intermediate bottom section unapplied;

Figure 5 is a view in perspective of a wall section unapplied;

Figure 6 is a view in perspective of an end top section unapplied;

Figure 7 is a view in perspective of an intermediate top section unapplied;

Figure 8 is an enlarged sectional view taken substantially on the line 8—8 of Figure 2;

Figure 9 is an enlarged sectional view taken substantially on the line 9—9 of Figure 2;

Figure 10 is a view in perspective illustrating an end top section constructed in ac-

cordance with a further embodiment of my invention.

As herein disclosed, my improved culvert comprises a plurality of bottom sections 60 formed of suitable reinforced cementitious material, the end sections 1 being each of a length substantially equal to one-half of the length of the intermediate sections 1^a. The sections 1 and 1^a are provided along their side 65 or longitudinal marginal portions with the upstanding pins 2 which are adapted to be received within the recesses or sockets 3 provided in the lower edges of the side wall sections 4, said sections 4 being also preferably 70 made from suitable cementitious material. It is to be particularly noted that the assembly of the side wall sections 4 with respect to the bottom sections 1 is such that the sections 4 lap adjacent sections 1 whereby a 75 substantial and rigid structure is assured.

The upper marginal portion of each of the wall sections 4 midway its ends is provided with a recess 5 while the ends thereof are provided with the notches 6, each of said 80 notches 6 being substantially equal to one-half of a recess 5. The base wall *a* of each of the notches 6 is provided with an upstanding pin 7 while the opposite end portions of the base wall *b* of the recess 5 are 85 provided with the upstanding pins 7'.

The culvert top also comprises a plurality of separable sections formed of suitable reinforced cementitious material with each of the end sections 8 of a length substantially 90 equal to the length of an end bottom section 1 and each of the intermediate sections 8^a of a length substantially equal to an intermediate bottom section 1^a.

Each of the sections 8 or 8^a has its side 95 or longitudinal marginal portions provided with depending flanges 9 adapted to overlie the outer faces of the upper portions of the wall sections 4 when said top section is in applied position and disposed through 100 each of said flanges 9 and the overlying portion of a side wall are the holding bolts 10 to provide means for maintaining the top section in proper assembled relation. Each of the top end sections 8 is provided at its inner end with a transversely disposed reinforcing flange or web 11 the extremities 105 of which being adapted to be received in the forward portions of the recesses 5 provided in the sections 4 upon which the section 8 is mounted. The intermediate portion 110 of this web or flange 11 is extended

downwardly to provide shoulders 12 for close contact with the inner faces of the co-acting wall sections 4 whereby said sections are effectively held against inward movement and the rigidity of the structure further maintained.

The outer or opposite extremity of the top end section 8 is provided with a header flange 14 the lower marginal portion of which being provided with the recesses 15 to receive the base portions of the outer end notches 6, the intermediate wall *a* of each of said recesses 15 being provided with a recess or socket 16 to receive an upstanding pin 7 as carried by the base wall *a* of said outer recess 6.

Each of the intermediate sections 8^a is provided at its extremities with the transversely disposed depending reinforcing flanges or webs 17 the extremities of which are partially received in the inner portions of the recesses 5 of adjacent wall sections 4 and are provided with the shoulders 18 having close contact with the opposed faces of the sections 4.

The central portion of each of the intermediate top sections 8^a is also provided with a transversely disposed bracing flange or web 19 of a width to be snugly received within notches 6 at the adjacent or meeting ends of the wall sections 4 and also provided with the shoulders 20 for close contact with the opposed faces of said sections.

The extremities of the flanges 11, 17 and 19 are provided with the recesses or pockets 21 to receive the remainder of the pins 7 and 7'.

To further hold the top sections in assembled relation the adjacent flanges 11 and 17 have disposed therethrough the holding bolts 22.

In the embodiment of my invention as illustrated in Figure 10, an end top section 8^{''} has its header flange 14' separately formed which is of material advantage in transportation and assembly. This sepa-

rable header flange 14' is provided adjacent its opposite ends with the outstanding flanges 9' which are adapted to be bolted to the adjacent side wall sections 4 while the intermediate portion of said header flange is adapted to be bolted to a depending flange 17' carried by the adjacent end of the section 8^{''} proper.

From the foregoing description it is thought to be obvious that a road culvert constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A culvert comprising a bottom wall, side walls having recesses in their upper marginal portions, a top wall resting upon the side walls, said top wall being provided therewithal with depending transversely disposed reinforcing flanges, the flanges being received within the recesses of the side walls.

2. A culvert comprising a bottom wall, side walls having recesses in their upper marginal portions, a top wall resting upon the side walls, said top wall being provided therewithal with depending transversely disposed reinforcing flanges, the flanges being received within the recesses of the side walls, said top wall being sectional, and means for connecting a flange of one section to the flange of an adjacent section.

In testimony whereof I hereunto affix my signature.

JAMES M. MORGAN.
